UNITED STATES PATENT OFFICE.

WILLIAM E. RANNEY, OF COLUMBUS, OHIO, ASSIGNOR TO THE PERFECTION MORTISER COMPANY, OF COLUMBUS, OHIO, A CORPORATION OF OHIO.

MORTISING MACHINE.

Application filed August 21, 1924. Serial No. 733,436.

This invention relates to improvements in wood working machines and is especially directed to an improved mortising machine designed for the purpose of cutting or forming mortises in doors, sashes or the like in a quick, convenient and economical manner.

The invention is particularly directed to the provision of a mortising machine wherein the wood cutting bit is operated by means of an electric motor, by means of which the output of the machine is materially increased over the ordinary type of hand operating machine, less labor required in effecting its operation and control and wherein the construction of the machine is greatly simplified by the elimination of the many trains of mechanisms involved in the ordinary hand type of machine.

A further object of the invention resides in the provision of a motor for effecting the operation of the cutting bit of the machine and in the provision of an improved hand regulated means by means of which the oscillatory motion of the bit is controlled and the infeed movement of the bit governed.

With these and other objects in view, as will appear as the description proceeds, the invention consists in the novel features of construction, combinations of elements and arrangements of parts hereinafter to be fully described and pointed out in the appended claims.

In the drawings:

Figure 1 is a side elevation of my improved mortising machine,

Figure 2 is a vertical section taken through the machine on line 2—2 of Figure 1,

Figure 3 is a top plan view, and

Figure 4 is a vertical section on the line 4—4 of Figure 1.

Referring more particularly to the details of the invention the numeral 1 designates an improved mortising machine in its entirety. This machine comprises broadly a frame 2, a carriage 3 mounted on the frame for longitudinal travel, an electric operating motor 4, a bit 5, and means of a manually operated character for governing the oscillation of the bit and the infeeding movement thereof.

The frame consists of a channel shaped lower section 7 which is arranged to fit over the edge of a door sash as disclosed in Figures 1 and 2. The side walls of the section 7 are provided at their opposite ends

with threaded openings for the reception of clamping screws 8, which are adapted to press on the opposite sides of the door to rigidly retain the frame 2 in an operative position of application on the door.

Extending perpendicularly from the lower section 7 are rods 9, which have their outer ends united by means of a transverse cross piece 10. This construction renders the frame substantially rectangular and provides a frame of all needed strength and durability to carry out the successful use of the machine. Mounted upon the rods 9 for longitudinal adjustment thereon is a traveling carriage 11. This carriage has its ends formed with sleeve shaped extensions 12 having bores provided therein for the reception of the rods 9. By means of this construction the carriage is permitted to traverse the frame longitudinally but is restrained from rotation or undue flexing. Between the sleeves 12 the carriage is formed to include outwardly bowed or curved side walls 13 between which is positioned the operating motor 4. The frame of this motor is surrounded by a collar 14, and trunnion pins or studs 15 are arranged to project into registering openings provided in said collar and formed in the side walls 13 of the carriage. This construction serves to securely retain the motor within the carriage but admits of rocking or oscillatory movement on the part of the motor with respect to the carriage. The lower end of the motor has its armature shaft 16 formed with a chuck 17 adapted for the removable reception of a cutting bit 18, which is rotated by the motor for the purpose of producing the necessary cutting action.

In order to oscillate the motor back and forth so that its associated cutting bit will be given the desired range of travel necessary in producing a mortise socket, the side walls 13 of the carriage are extended to provide bearing sleeves 19, in which is journaled for rotation a transversely extending operating shaft 20. This shaft is equipped with a manually operated crank 21 by means of which the shaft may be conveniently rotated by the operator. The other end of the shaft is provided with a short crank 22 having a longitudinal groove 23 in its outer face. Arranged to be locked in any position throughout the length of the groove 23 is a slidable block 24 to which is pivoted one end of a

link 25, having its other or inner end pivotally connected as at 26 with an upstanding arm 27 integrally formed with the collar 14. It will be seen that by the rotation of the shaft 20 the crank and link connection associated therewith will result in the oscillation of the motor 4 and the consequent oscillation of the cutting bit. Also, it will be obvious that by adjusting the position of the block 24 within the crank 22 the throw of said crank may be readily governed, thus enabling the bit to produce mortises of varying length. In the event that the block is positioned in registration with the operating shaft 20, oscillation of the motor will be prevented so that the bit may be employed for drilling straight holes. The motor 4 is of the ordinary electric type standard in hand drills and is adapted to operate on ordinary voltages as are common in house circuits.

To govern the infeeding movement of the bit there is provided a feeding screw 28. This screw has its threaded shank received loosely within an opening 29 provided in the cross piece 10 of the frame. A spring pressed plunger 30 is mounted in connection with said cross piece and has its inner end normally projected into the threads of the screw 28. By pressing the plunger outwardly the screw will be relieved from engagement with the frame 2, thereby permitting the carriage to be quickly adjusted with respect to said frame. Upon release of the plunger the latter will assume its normal position serving in the capacity of a nut for the screw. The lower end of the screw is swiveled in connection with the carriage 3, as indicated at 31, so that when the screw is rotated the carriage may be moved longitudinally of the frame. To effect the rotation of this screw it is necessary merely to provide the operating shaft 20 with a beveled gear 32 meshing with a similar gear 33 provided on the lower end of the screw shaft.

Thus as the motor is oscillated through the rotation of the shaft 20, the screw 28 will be rotated to advance the bit on its infeeding movement.

In view of the foregoing description, taken in connection with the accompanying drawings, it will be seen that there is provided a mortising machine consisting of but few and simple parts, readily controlled and wherein the mechanical complication so largely present in hand operated machines has been eliminated. This is done in order to provide a practical machine for everyday work, one that can be readily kept in operative condition, and further of such design as to be capable of performing the operation of producing a mortise at a cost materially lower than by any other means of which I am aware.

What is claimed is:

1. In a mortising machine, a frame, a carriage mounted on said frame to traverse the latter longitudinally, a motor pivotally mounted upon said carriage, a cutting bit driven by the motor, and manually operated means for oscillating said motor and bit bodily.
2. In a mortising machine, a frame, a carriage slidably mounted upon said frame, a motor pivotally mounted upon said carriage and adapted to drive a cutting bit, and manually operated means for oscillating said motor and bit and effecting longitudinal travel of the carriage on said frame.
3. In a mortising machine, a frame, a carriage slidable on the frame, a motor pivoted to the carriage and provided with a cutting bit, a manually operated crank with pivotal connection between the crank and motor by means of which the motor is oscillated upon rotation of said crank, and means for effecting longitudinal travel of the carriage upon said frame during the rotation of said crank.

In testimony whereof I affix my signature.

WILLIAM E. RANNEY.
